(57) **CLAIM**

The ornamental design for a digital satellite receiver cover, as shown and described.

DESCRIPTION

FIG. 1 is a front perspective view of the enclosure for a digital satellite receiver cover;

FIG. 2 is another front perspective view thereof;

FIG. 3 is a back perspective view thereof;

FIG. 4 is another back perspective view thereof;

FIG. 5 is a partially exploded view thereof;

FIG. 6 is a partial top perspective view thereof;

FIG. 7 is a partial front perspective view thereof;

FIG. 8 is another partial top perspective view thereof;

FIG. 9 is a disassembled front perspective view thereof

FIG. 10 is a skeletal front view thereof;

FIG. 11 is a front view of the bezel shown separately for ease of illustration; and,

FIG. 12 is a front view of the navigation pad shown separately for ease of illustration.
